UNITED STATES PATENT OFFICE.

IRVING L. BROWN, OF CHICAGO, ILLINOIS, ASSIGNOR TO AMERICAN HOMES BUREAU,
OF CHICAGO, ILLINOIS, A CORPORATION OF ILLINOIS.

DESIGN FOR A BADGE.

Application filed April 21, 1924. Serial No. 9,344. Term of patent 3½ years.

To all whom it may concern:

Be it known that I, IRVING L. BROWN, a citizen of the United States, residing at Chicago, in the county of Cook and State of Illinois, have invented a new, original, and ornamental Design for Badges, of which the following is a specification, reference being had to the accompanying drawing, forming part thereof.

I claim:

The ornamental design for a badge, as shown.

IRVING L. BROWN.
